CHEST

John J. Lubberts and Lambert J. Mulder, Grand Rapids, Mich., assignors to Tomlinson of High Point, High Point, N. C., a corporation of North Carolina

Application March 8, 1957, Serial No. 45,154

Term of patent 14 years

(Cl. D33—19)

Figure 1 is a front-perspective view of the chest with the closure for the writing compartment in closed position; and

Figure 2 is a front perspective view of the chest with the closure for the writing compartment in open position.

The rear portion of the chest is conventional, and both sides thereof are the same.

We claim:

The ornamental design for a chest, substantially as shown and described.
